UNITED STATES PATENT OFFICE.

FREDERICK BUSSE, OF NEW YORK, N. Y.

DESIGN FOR A BADGE.

No. 38,033.

Specification for Design.

Patented May 29, 1906.

Application filed April 16, 1906. Serial No. 312,037. Term of patent 7 years.

To all whom it may concern:

Be it known that I, FREDERICK BUSSE, a citizen of the United States, residing at the city of New York, borough of Manhattan, in the county and State of New York, have invented a new, original, and ornamental Design for a Badge, reference being had to the accompanying drawing.

The figure is a front elevation, partly in perspective, of a badge, showing my new design.

I claim—

The ornamental design for a badge, as shown.

FREDERICK BUSSE.
